(57) **CLAIM**

The ornamental design for a food container, as shown and described.

DESCRIPTION

FIG. 1 is a perspective view of a food container.

FIG. 2 is a first side plan view of the food container of FIG. 1.

FIG. 3 is a second side plan view of the food container of FIG. 1.

FIG. 4 is a top view of the food container of FIG. 1.

FIG. 5 is a bottom view of the food container of FIG. 1; and, FIG. 6 is a cross sectional view along line 6-6 indicated in FIG. 4.

The broken line showing of the container is included for purposes of illustrating environment and forms no part of the claimed design.
